UNITED STATES PATENT OFFICE.

FRED W. OPP, OF SANTA ANA, CALIFORNIA.

AUTOMATIC HEADLIGHT CONTROL.

1,186,028.

Specification of Letters Patent. Patented June 6, 1916.

Application filed February 5, 1914. Serial No. 516,861.

To all whom it may concern:

Be it known that I, Fred W. Opp, a citizen of the United States, residing at Santa Ana, in the county of Orange, State of California, have invented new and useful Improvements in Automatic Headlight Controls, of which the following is a specification.

This invention relates to an automatic headlight control for vehicles; and the invention particularly has to do with the provision of novel mechanism for causing the projection of light from a head light to either side in coöperation with the turning 15 of the steering mechanism of the vehicle in either direction.

Although my invention may be applied to a vehicle of any class, I prefer to explain its working in connection with an automobile. 20 I employ a headlight or headlights, with a movable lens, preferably in the form of a movable reflector behind the source of illumination. This movable reflector is preferably mounted upon a central vertical axis 25 and may be displaced in either direction of rotation from its normal position, reflecting the light in either direction to the right or left from the line straight ahead. I preferably employ electro-magnetic means for 30 moving the lens; and my electro-magnetic means includes a plurality of sets of magnets adapted to give the lens a small or large displacement in either direction. I provide means in coöperation with the steering mechanism of the vehicle for properly energizing the electro-magnets; so that when the steering mechanism is slightly turned in either direction, the corresponding electro-magnet is energized to slightly displace the lens in 35 a corresponding direction. When the steering mechanism is turned farther in either direction, the corresponding electro-magnetic means will be energized to turn the lens farther in the corresponding direction. 40 I also provide means so that the lens may be manually turned in either direction to throw the light to either one side or the other at will.

In the accompanying drawings, Figure 1 45 shows an automobile equipped with a preferred form of my device. Fig. 2 is a longitudinal vertical section of my improved headlight, Fig. 3 is a horizontal section taken as indicated by line 3-3 of Fig. 2, Fig. 4 is a section taken as indicated by line 4-4 of Fig. 2, Fig. 5 is a diagram showing

the electrical connections of my device, Figs. 6, 7 and 8 are views similar to those of Figs. 2, 4 and 5, showing a modified form of device.

In the drawings, the numeral 10 may designate an automobile typical of any vehicle having steering mechanism which may comprise forward steering wheels 11, conductive media 12, steering post 13, and steering gear 14 with a gear shaft 15. It will be understood that I may make my electrical connection to the steering mechanism at any convenient point; but, for the purpose of illustration, I have shown my electrical apparatus as connected directly with the shaft 15 of the steering gear 14.

Any number of headlights may be used and controlled by my mechanism. I herein explain my mechanism as for a single headlight 20, mounted centrally upon the forward part of the automobile. This headlight 20 has a suitable casing or body 21 within which there is a source of illumination 22 of any desired character. A movable lens is used to project the illumination from the source 22; and I prefer to use a reflective lens 23 mounted upon central vertical pivots 24 carried in ball bearings 25 so that the lens may be easily turned. Above 30 the reflecting lens 23 the upper pivot 24 extends to form a shaft 24^a and carries a head 26 on its upper end below which a spring 27 is confined. This spring 27 presses downwardly upon a disk or collar 28 engaging a stationary disk 29. The upper disk 28 is constrained to rotate with the shaft 24^a but may slide vertically thereon while the lower disk 29 is stationary on a frame 30. The two disks have complementary V-shaped surfaces as shown at 31 in Fig. 4; and the action of spring 27 pressing the upper disk against the lower one is to always bring the reflector 23 back to its normal central position, in which position it projects the light from the source of illumination straight ahead.

In the rear part of the lamp body I may provide two sets of electro-magnets 35 and 36. The magnets of each set are mounted upon opposite sides of the body as is best shown in Figs. 3 and 4. Each of the magnets is equipped with a suitable armature 37 or 38; and all the armatures are connected by suitable connecting arms 39 or 40 with a socket 41 projecting rearwardly from the reflector 23. The ends of the con-

necting arms 39 and 40 have balls 42 which enter the socket 41; and a certain amount of looseness is provided for each ball in the socket so that the movement herein described of the reflector may take place. Longitudinal slip-joints 39^a and 40^a are also provided in the arms 39 and 40. It will be noted that the armatures 38 have relatively short movement when attracted by the magnets 36 and that armatures 37 have a relatively longer movement when attracted by their electro-magnets 35. When it is desired to displace the reflector 23 slightly from its normal position, either one or the other of magnets 36 is energized; while for a longer movement in either direction either one or the other of magnets 35 is energized. The mechanism of energization is illustrated best in the diagram of Fig. 5. I may mount a suitable commutator 70 on the shaft 15 and this commutator 70 may have four contacts 41, 42, 43, 44. Two brushes 45 and 46 may engage the contacts as the commutator is rotated. In the normal position of the commutator, corresponding to the normal straight ahead position of the steering mechanism of the vehicle, neither of the brushes engages any of the contacts. Suppose now that the steering gear is turned so as to turn the vehicle to the right. In the present described arrangement this would turn the commutator in the direction indicated and would immediately engage the contact 44 with brush 46. Current would then flow from the battery 47 through wire 48, wire 49, brush 46, wire 50 to electro-magnet 36 positioned on the left in Fig. 4 which would immediately cause the displacement of the reflector 23 in the direction indicated and would cause projection of light to the right. Further movement of the steering mechanism would cause engagement of the contact 43 with the brush 46 and would cause passage of current through wire 51 to magnet 35 positioned on the left in Fig. 4, which would cause further movement of the reflector in the direction indicated, and cause the light to be projected farther to the right. On contrary motion of the steering mechanism, contacts 41 and 42 would be respectively engaged with brush 45 and current would be successively sent through wires 52 and 53 to the electro-magnets 36 and 35 on that side, causing displacement of the reflector 23 in a direction opposite to that indicated and causing the projection of the light to the left. I may provide suitable push buttons or suitable switches, connected between wire 48 and wires 51 and 53 as shown at 55; whereby the driver may cause either of the magnets 35 to be energized and cause the light to be thrown either to right or left at will. Common wire 54 leads back from the electro-magnets to the battery.

65 In Figs. 6, 7 and 8 I have shown a modi-

fied form of device. Here the parts are substantially as before explained excepting that the magnets 35 and 36 are displaced by a pair of double wound solenoids 60. Each solenoid has two windings 35^b and 36^b, and a single armature core 37^b is acted upon by all four windings. The stud 41^b projecting from the reflector 23 connects directly with the core 37^b so that movement of the core directly causes movement of the reflector. Energization of either of windings 36^b will cause a small displacement of the lens; energization of either winding 35^b will cause a larger displacement. Energization is effected substantially as hereinbefore described and as indicated in the diagram of Fig. 8.

These typical embodiments of my invention serve to show the scope thereof. My invention is not limited to the precise details herein explained, which may be varied to suit conditions.

I claim—

1. A headlight, comprising a body, a source of illumination, a reflector mounted on a vertical pivot, magnetic means for slightly displacing the lens in either direction of rotation, and magnetic means for further displacing the lens in either direction of rotation.

2. In combination, a vehicle with steering mechanism, a headlight, comprising a body, a source of illumination, a reflector mounted on a vertical pivot, magnetic means for slightly displacing the reflector in either direction of rotation, and magnetic means for further displacing the reflector in either direction of rotation and means co-operating with the steering mechanism for first energizing the first mentioned electro-magnetic means and then energizing the second mentioned electro-magnetic means as the steering mechanism is displaced in either direction from normal position.

3. In combination, a headlight comprising a body, a source of illumination therein, a pivotally mounted reflector adjacent the illumination source, electro-magnetic means for slightly displacing the reflector about its pivot, electro-magnetic means for further displacing the reflector about its pivot, and means for energizing either electro-magnetic means.

4. In combination, a vehicle with steering mechanism, a headlight comprising a body, a source of illumination therein, a pivotally mounted reflector adjacent the illumination source, electro-magnetic means for slightly displacing the reflector about its pivot, electro-magnetic means for further displacing the reflector about its pivot; and means for successively energizing said electro-magnetic means comprising means for energizing the first mentioned electro-magnetic means and then energizing said second

mentioned electro-magnetic means as the steering mechanism is turned from normal position.

5. In combination, a vehicle with steering mechanism, a headlight with a source of illumination and a reflector movably mounted behind the source, means for slightly displacing the reflector to reflect the light from the source slightly to one side of its normal line of reflection, means to further displace the reflector to reflect the light from the source farther from its normal line of reflection, and means to successively actuate said reflector displacing means as the steering mechanism is turned from its normal position embodying means for energizing the first mentioned means when the steering mechanism is turned slightly and for energizing the second mentioned means when the steering mechanism is turned farther.
10. In combination with a vehicle having steering mechanism, a headlight with a source of illumination and a reflector movable to reflect the light to one side of its normal line of reflection, means which when energized will move the reflector imme-
15. In combination with a vehicle having steering mechanism, a headlight with a source of illumination and a reflector movably mounted behind the source, means for slightly displacing the reflector to reflect the light from the source slightly to one side of its normal line of reflection, electro-magnetic means which when energized will move the reflector immediately and suddenly to a certain definite position in which it reflects the light to one side, and means including a switch actuated by the steering mechanism after it has been turned through a certain predetermined movement to energize said reflector moving means.
20. In combination with a vehicle having steering mechanism, a headlight with a source of illumination and a reflector movably mounted behind the source, means for slightly displacing the reflector to reflect the light from the source slightly to one side of its normal line of reflection, electro-magnetic means which when energized will move the reflector immediately and suddenly to a certain definite position in which it reflects the light to one side, and means including a switch actuated by the steering mechanism after it has been turned through a certain predetermined movement to energize said reflector moving means.
25. In combination with a vehicle having steering mechanism, a headlight with a source of illumination and a reflector movably mounted behind the source, means for slightly displacing the reflector to reflect the light from the source slightly to one side of its normal line of reflection, electro-magnetic means which when energized will move the reflector immediately and suddenly to a certain definite position in which it reflects the light to one side, and means including a switch actuated by the steering mechanism after it has been turned through a certain predetermined movement to energize said reflector moving means.

diately and suddenly to a certain definite position in which it reflects the light to one side, and means actuated by the steering mechanism after it has been turned through 30 a certain predetermined movement to energize said reflector moving means.

7. In combination with a vehicle having steering mechanism, a headlight with a source of illumination and a reflector movably mounted behind the source, means for slightly displacing the reflector to reflect the light to one side of its normal line of reflection, electro-magnetic means which when energized will move the reflector immediately and suddenly to a certain definite position in which it reflects the 35 light to one side, and means including a switch actuated by the steering mechanism after it has been turned through a certain predetermined movement to energize said reflector moving means.

In witness that I claim the foregoing I have hereunto subscribed my name this 23d day of January 1911.

FRED W. OPP.
